UNITED STATES PATENT OFFICE.

JAMES A. LINN, OF NEW PHILADELPHIA, AND JACOB GEIB, OF STEUBENVILLE, OHIO.

CASTER.

SPECIFICATION forming part of Letters Patent No. 790,733, dated May 23, 1905.

Application filed July 12, 1904. Serial No. 216,277.

To all whom it may concern:

Be it known that we, JAMES A. LINN, residing at New Philadelphia, in the county of Tuscarawas, and JACOB GEIB, residing at 5 Steubenville, in the county of Jefferson, State of Ohio, citizens of the United States, have invented new and useful Improvements in Casters, of which the following is a specification.

Our invention relates to improvements in 10 that class of devices known as "casters."

Said invention or caster has for its object 15 to provide for its ready and effective application or attachment to the article or object in connection with which it is to be used—as, for instance, heavy boxes, more particularly coffin rough-boxes—for conveniently moving them as in shipping the same, and which caster shall be readily detachable from such object or box.

20 Said invention is characterized for simplicity, lightness, yet being substantial, and cheapness of manufacture; and it consists of certain structural details substantially as hereinafter more fully disclosed, and particularly 25 pointed out by the claims.

In the accompanying drawings, illustrating 30 the preferred embodiment of our invention, Figure 1 is a plan view thereof. Fig. 2 is a view looking directly at the angle of the 35 bracket or casting of the caster. Fig. 3 is a side view, and Fig. 4 is a vertical central section of the invention.

In the carrying out of our invention we 40 produce a bracket or casting 1, preferably in general outline V shape in horizontal or cross-section and with an integral tubular extension or socket 1^a at the angle resulting from such shape to receive the spindle 2^a of the 45 caster-wheel 2, within which socket said spindle is suitably and fixedly held, the divergent portions resulting from the peculiar or V form of the bracket or casting 1 or upstanding lateral wings or plates, adapted to embrace right-lined surfaces at right angles to each other, the angle formed on the latter being received within the reentrant angle of the former, the practical application of which will be apparent later. Said caster-wheel 2 has its axle or journal 2^a hung or secured in

a preferably malleable-metal stirrup or bearing 50 2^b, with the uniting portion between the arms of said stirrup looped, as at 2^d, to form substantially an eye to receive said spindle and permit the swiveling action of said stirrup or bearing upon the latter. Said stirrup or bearing is suitably held as against vertical displacement by a collar 2^c, located upon the spindle 2^b in between the stirrup 2^b and the bracket 1, and a ring or shoulder 2^{dd} upon said spindle arranged below said 55 stirrup. Said bracket or casting 1 by reason of its above-noted outline or contour is adapted, as will be observed, to snugly fit directly upon the corner of the box or other like object with its upstanding divergent portions or wings engaging surfaces of the latter at right angles to each other. Said wings or divergent portions are provided with preferably countersunk openings 1^b to receive 60 screws or like fastenings to aid the securing 70 of said bracket or casting in place upon the box-corner. Said bracket or casting has a transverse member 1^c extending from the bottom edges of the wings thereof and at the most distant or divergent points therebetween 75 to enable said transverse or horizontal member to take under the box. Said bottom member 1^c has about at the center of its upper surface an upstanding pointed teat or penetrating-fastening 1^d, adapted to be readily driven 80 into or penetrate the bottom of the box from the under side to further aid the securing of the caster-bracket upon the latter. Said bracket or casting has, as it were, a lower portion of its angle removed or cut away 85 along a line extending or curving from the lower end of the socket 1^a downward and inward through the wings of said bracket, terminating at the bottom surface of said wings short distances from the inner vertical edges 90 of the last named, producing an opening 1^e in said bracket, initially receiving the bottom corner edge of the box. Said corner edge of the box, however, is removed or reduced sufficiently to take it out of the way of the swing 95 or play of the caster wheel or roll, as when moving the box.

Latitude is allowed as to details herein, as

they may be changed as circumstances suggest without departing from the spirit of our invention.

We claim—

- 5 1. A caster comprising a frame or bracket having upstanding or plate-like divergent portions or wings adapted to embrace right-lined surfaces at right angles to each other, and having a spindle-receiving socket at their points of convergence standing beyond the plane of said bracket, said wings having their lower edges removed from the lower end of said socket downward and inward suitably to permit the play or swing of the caster-wheel carrying stirrup or bearing within the plane of said frame or bracket and outward from, and in a plane above the bottom edge of said bracket or frame.
- 10 2. A caster having its bracket formed with divergent wings and a spindle-receiving socket arranged at the convergent or meeting portions of said wings, said wings having their lower edges cut away or extending from the lower end of said socket inward and downward suitably to permit the play or swing of the caster-wheel carrying stirrup or bearing within the plane of said bracket, said wings also having at their bottom divergent edges, a connecting-bar adapted to effect connection therebetween and the article to which the caster may be applied.

- 15 3. A caster having its bracket formed with divergent wings, and a spindle-receiving socket arranged at the convergent or meeting portions of said wings, said wings having their lower edges cut away or extending from the lower end of said socket inward and downward suitably to permit the play or swing of the caster-wheel carrying stirrup or bearing within the plane of said bracket, said wings also having at their bottom divergent edges, a connecting-bar equipped with a penetrating 40
teat or fastening.

In testimony whereof I have signed my name to this specification, at New Philadelphia, in 45 the county of Tuscarawas and State of Ohio, this 28th day of June, 1904, in the presence of two subscribing witnesses.
